UNITED STATES PATENT OFFICE

154,997

DESIGN FOR A SPOON HOLDER

Charles Elser, Clementon, N. J.

Application March 17, 1948, Serial No. 145,180

Term of patent 7 years

(Cl. D44—29)

To all whom it may concern:

Be it known that I, Charles Elser, a citizen of the United States, residing at Clementon, in the county of Camden and State of New Jersey, have invented a new, original, and ornamental Design for Spoon Holders, of which the following is a specification, reference being had to the accompanying drawing, forming part thereof, in which

Figure 1 is a top plan view of a spoon holder embodying the design;

Fig. 2 is a side elevation thereof;

Fig. 3 is an end elevation thereof; and

Fig. 4 is a longitudinal section thereof taken on the line 4—4 of Fig. 1.

I claim:

The ornamental design for a spoon holder, as shown.

CHARLES ELSER.
